DOOK HENG LAU, OF PARIS, FRANCE

ADVERTISING APPARATUS

Application filed November 14, 1927, Serial No. 233,256, and in France November 22, 1926.

Advertising devices are already known in which the advertising objects, such as signs or pictures are mounted upon rods which are assembled in magazines and the said objects 5 are caused to travel in succession before the public eye.

The present invention relates to an apparatus of this class which affords various practical advantages for advertising purposes.

In my said apparatus, suitable racks or the like, are employed to take up each sign or picture and to transport it from one magazine to another; to the said racks is preferably 15 given a straight reciprocating motion by means of motor power or by hand. I prefer to employ a first set of racks to transport the said rods from a first magazine to a second, and a second set of racks to convey the rods 20 from the second magazine to the first; the said racks are preferably connected together by flexible means such as a chain coacting with supporting pulleys.

I will describe a practical construction for 25 the mechanism actuating the said racks as follows:

The motor drives indirectly a wheel which carries a toothed sector at its periphery; which sector engages at different times with 30 two respective pinions, and each pinion indirectly drives a corresponding rack.

The magazines may be disposed as follows:

The rods are placed upon a stationary toothed member; adjacent this member, a 35 movable toothed member, which is given a reciprocating motion, raises the said rods and causes them to move forward, tooth by tooth, towards the outlet of the magazine.

The reciprocating motion of the movable 40 toothed member may be obtained by means of an eccentric or the like adapted to give the said member a vertical reciprocating motion, while a second eccentric (or cam) or the like 45 gives it another lateral reciprocating motion spaced at 90 degrees from the first.

By way of example and for the proper understanding of the following description, I have represented in the appended drawings 50 an embodiment of the present invention.

Fig. 1 is a sectional and elevational view of the apparatus.

Fig. 2 is a detail view of the upper magazine.

In the example herein represented, the 55 mechanism as a whole is housed in a case 1 whose two sides serve to display the signs or pictures, each side comprising two apertures or windows 2, placed respectively at the upper and the lower part, thus providing four 60 windows in all for the display of the signs.

The advertising signs are mounted upon rods 23 (Fig. 2) whereby they may be displaced or stowed away in the manner to be further disclosed.

The mechanism comprises two similar devices and only one device is shown on Figure 1. Each device comprised two parts, firstly magazines or storage devices, and secondly a set of racks which are adapted to transfer 70 the advertisements successively from one magazine to the other.

1. Rack movement

The device is operated by a chain 40 driving a chain wheel 4; upon the wheel shaft is keyed a pinion 6 coacting with a gear wheel 50; said wheel carries at one side and for about $\frac{1}{4}$ the periphery a toothed sector 52 which alternately engages the gear wheels 80 53 and 54. The wheel 53 actuates the rack 59 by means of the gearing 55—56—57—58. The wheel 54 actuates the other rack 63 by means of the gearing 60—61—62. A pinion 75 engages both gear wheels 56 and 60.

Each rack is guided by rollers 64 and is thus respectively held against the driving pinion 58 or 62. A chain 65 attached to the top of the racks is disposed upon the supporting pulleys 66—67.

2. Movement of the magazines or storage devices

The said devices are operated by the pinion 76 and the chain 7 which drives the pulleys 95 8 and 9. The chain 46 disposed on the chain wheel 12 drives the upper device, and the chain 68 drives the lower device. Fig. 2 shows on a larger scale, the device contained in the upper magazine; it comprises a stationary 100

plate 14 provided on the upper edge with the teeth 15. A movable toothed plate 16 is held against the stationary plate 14 by the stationary guides 17.

The movable toothed plate 16 is given a vertical reciprocating motion in the following manner. The lower edge of the plate 16 is controlled by a lever 42 at whose middle part is disposed a steel ball 43 coacting with an eccentric 18 mounted on the shaft of the gear wheel 13, which is driven by the chain 46. The movable plate 16 is also given a lateral motion, and for this purpose a wheel 44 keyed to the shaft of the wheel 13, carries a finger 19 coacting with the levers 20 which are pivoted to the fixed plate 14 and whose fork-shaped ends coat with the studs 21 secured to the toothed plate 16; said studs are movable in straight slots 22 provided in the plate 14.

20 The operation of the apparatus is as follows:

In the position shown in Figure 1 the wheel 50 turns according to the arrow 70, and the toothed sector 52 will now engage the pinion 58, so that the pinion 58 rotating in the direction of the arrow 61 will raise the rack 59. During the same time, the wheel 56 engaging the pinion 75, causes the wheel 62 to rotate by means of the wheels 60 and 61, so that the rack 63 goes down.

35 The rack 59 lifting, the fork 69 provided at the upper part of the said rack, raises the rod 23 situated in the last tooth of the plate of the lower magazine. When the said rod 23 approaches the upper magazine, it meets the stud 72, and pushes it upward, and after the rod is passed, the stud 72 will return to its original position, so that when the rack 59 descends, the rod will be caught by the stud 72 and thus sending it to the first tooth of the plate 15. The sign will hence be in full view to the public through the window 2.

45 The alternate motion of the toothed member 16 due to the eccentric 18 and the arm 19 will cause the rod 23 to move forward tooth by tooth and during this time other cards or signs will successively take the place of one another. During this time the wheel 50 continues to rotate in the direction of the arrow 70, and at a certain moment the toothed sector 52 will engage the pinion 54, so that the wheels are turning in an opposite direction, as mentioned previously, thus causing 50 the rack 63 to rise and the rack 59 to descend.

55 As the fork 73 of the rack 63 passes the upper plate, the point of the fork 73 receives the rod 23 from the last tooth of the plate 15. The sector 52 then engages the pinion 53, so 60 that the rack 59 will again rise, as stated, and the rack 63 will descend drawing down the rod 23 together with the signs or pictures which it supports towards the lower chamber.

65 When at the bottom of the stroke, the stud 74 of the fixed toothed plate in the lower

magazine will receive the rod 23 which drops down on the first tooth of the lower fixed plate.

The size and shape of the toothed wheels actuating the racks, and also driving the mechanism in the said magazine, are such that each up and down movement of the racks corresponds to a complete movement of the said movable toothed member in each magazine.

70 The upper stationary plate 14 is made shorter than the corresponding lower stationary plate, since the upper stationary plate must leave a sufficient space for the rise and descent of the rod 23. The toothed part of the movable plate 16 has one tooth less than the fixed toothed part in the lower and upper magazine.

75 With the said apparatus I obtain an advantage which consists in the fact that the interior may be lighted permanently or otherwise, so that the apparatus will be adapted for day or night uses.

80 Obviously, the advertising object suspended from the said rods may be replaced by any other suitable objects or articles such as textile fabrics, lace, or the like.

85 In the stationary plate 14 of the upper mechanism I employ in all cases a tooth which is not utilized, as also in the lower mechanism, whereby the advertising object 90 may be readily changed.

95 Leaving empty spaces between the rods, it is possible to have during a specified longer time the objects in view of the public, without readjusting the mechanism.

100 It will be noted that this apparatus can have four signs shown at the same time.

Having now particularly described my invention and in what manner the same is to be performed, I claim as my invention:

1. Publicity apparatus for presenting objects suspended on rods, comprising an upper magazine and a lower magazine in which the ends of the rods bear on fixed toothed members, movable toothed members arranged parallel along each fixed toothed member, an eccentric actuated by a chain directly actuating each movable toothed member, two groups of vertical racks, one in front, the other behind the magazines, and a toothed sector in continuous rotation, coming into engagement on the one hand with the pinion which controls the movement of the racks in one direction, and on the other with the pinion which controls the movement of the racks in the opposite direction.

2. An apparatus as claimed in claim 1, in which each of the mechanisms actuating the racks comprises a driving wheel, a toothed sector mounted thereon, two pinions engaging said sector at different times, and gearing disposed between each pinion and one of the racks.

3. An apparatus as claimed in claim 1, in

which the mechanism actuating the movable toothed member, comprises an eccentric imparting to said movable member a vertical reciprocating motion and a rotating finger 5 imparting to the said movable member a horizontal reciprocating motion.

4. An apparatus as claimed in claim 1, in which the racks are connected together in pairs by flexible connecting means coacting 10 with supporting pulleys in such manner that when one rack rises, the other will descend, and inversely.

5. An apparatus as claimed in claim 1, in which the toothed members carry lateral 15 studs adapted to raise the rods which are brought into position by the racks.
